UNITED STATES PATENT OFFICE.

JOHANN JACOB KNECHT, OF SCHÖNAU, NEAR CHEMNITZ, GERMANY, ASSIGNOR TO
FIRM MASCHINENFABRIK KAPPEL A. G., OF KAPPEL, NEAR CHEMNITZ, GERMANY.

EMBROIDERING-MACHINE.

1,160,417.

Specification of Letters Patent. Patented Nov. 16, 1915.

Application filed December 31, 1914. Serial No. 879,969.

To all whom it may concern:

Be it known that I, JOHANN JACOB KNECHT, citizen of the Confederation of Switzerland, residing at Schönau, near 5 Chemnitz, in the Kingdom of Saxony, Germany, have invented certain new and useful Improvements in Embroidering - Machines, of which the following is a specification.

My invention relates to embroidering machines and more especially to embroidering machines provided with a shuttle.

In sewing machines it is old to use curved shuttles moved by oscillating drivers substantially in a horizontal direction in curves 15 situated in horizontal or vertical planes. It has proved impossible to simply transfer this arrangement onto shuttle embroidering machines for the reason that in the case of a horizontal movement neither a simple and 20 reliable motion nor any desired relation can be obtained without impairing the capacity of the shuttles, while in the case of a vertical movement the shuttles are not sure to catch the needle thread loops, as they are 25 compelled to follow the vertical plane of the tissue and, unless being well guided, are apt to tip over.

My invention has for its object, in order to obtain a simple and effective shuttle driving device, to utilize the curved shuttles, hitherto used only in ordinary domestic sewing machines, in embroidering machines, at the same time avoiding the drawbacks mentioned above.

According to my invention the races of the curved shuttles, besides describing a convex curve toward the cloth plane, are also inclined in a direction transverse to such longitudinal curvature, thereby permitting 40 shuttles to move in a substantially inclined

direction and to safely catch the needle thread loop on account of their being pressed onto their races by their proper weight.

In the drawings affixed to this specification a preferred form of my device is shown. 45

Figure 1 is a side view, and Fig. 2 a back view of the shuttle race.

The shuttles 2 are driven by the drivers 3 up and down in the races 1 which races have a convex curvature toward the needles 4 and 50 are inclined laterally. It is thus rendered possible to move the driver bar by means of a shaft 6 having an oscillating and an axial movement. The shuttle races may either be cast or they may be pressed in one 55 piece with the threadways.

I claim:—

1. In an embroidering machine of the shuttle type, the combination with a needle, of a longitudinally curved shuttle race, said 60 race having a shuttle bearing surface inclined to the vertical, an elongated shuttle mounted in the race and above said bearing surface, and means for operating the shuttle adapted to follow the path thereof, for 65 the purpose specified.

2. In an embroidering machine of the shuttle type, the combination with a needle of a longitudinally curved shuttle race having a shuttle bearing surface inclined to the 70 vertical, an elongated shuttle mounted in the race and above said bearing surface, and an axially movable oscillating shaft for operating the shuttle.

In testimony whereof I affix my signature 75 in presence of two witnesses.

JOHANN JACOB KNECHT.
